(57) **CLAIM**

The ornamental design for an air chuck, as shown and described.

DESCRIPTION

FIG. 1 is a side view of an air chuck showing the new design;

FIG. 2 is a front view thereof;

FIG. 3 is a rear view thereof;

FIG. 4 is a top plan view thereof;

FIG. 5 is a bottom plan view thereof;

FIG. 6 is a side perspective view thereof;

FIG. 7 is an opposite side perspective view thereof;

FIG. 8 is a bottom and side perspective view thereof;

FIG. 9 is a bottom and opposite side perspective view thereof;

FIG. 10 is an alternate configuration of the design as described in FIG. 1;

FIG. 11 is an alternate configuration of the design as described in FIG. 2;

FIG. 12 is an alternate configuration of the design as described in FIG. 3;

FIG. 13 is an alternate configuration of the design as described in FIG. 4;

FIG. 14 is an alternate configuration of the design as described in FIG. 5;

FIG. 15 is an alternate configuration of the design as described in FIG. 6;

FIG. 16 is an alternate configuration of the design as described in FIG. 7;

FIG. 17 is an alternate configuration of the design as described in FIG. 8; and,

FIG. 18 is an alternate configuration of the design as described in FIG. 9.
